US00D396217S

United States Patent [19]

Suzuki

[11] Patent Number: Des. 396,217
[45] Date of Patent: **Jul. 21, 1998

[54] ELECTRONIC COMPUTER

[75] Inventor: Shogo Suzuki, Chiba-ken, Japan

[73] Assignee: Kabushiki Kaisha Toshiba, Kawasaki, Japan

[**] Term: 14 Years

[21] Appl. No.: 74,111

[22] Filed: Jul. 29, 1997

[30] Foreign Application Priority Data

Feb. 24, 1997 [JP] Japan 4917/1997
